UNITED STATES PATENT OFFICE.

FRED C. GIBBS, OF SOUTH PORTLAND, MAINE.

DESIGN FOR A MILK-BOTTLE HOLDER.

46,089.

Specification for Design.

Patented July 14, 1914.

Application filed April 16, 1914. Serial No. 832,399. Term of patent 14 years.

To all whom it may concern:

Be it known that I, FRED C. GIBBS, a citizen of the United States, residing at South Portland, in the county of Cumberland and State of Maine, have invented a new, original, and ornamental Design for Milk-Bottle Holders, of which the following is a specification, reference being had to the accompanying drawing forming part thereof.

Figure 1 is a perspective view of a milk bottle holder showing my new design. Fig.

2 is a side view of the same. Fig. 3 is a front view of the same.

I claim:—

The ornamental design for a milk bottle holder, as shown.

In testimony whereof I affix my signature, in presence of two witnesses.

FRED C. GIBBS.
